Columbus, Ind., a corporation of Indiana

Filed Oct. 31, 1960, Ser. No. 62,682

Term of patent 14 years

(Cl. D81—10)

Fig. 1

Fig. 2

FIG. 1 is an isometric view of a case for a portable heater showing our new design and illustrating the top and one side and end thereof;

FIG. 2 is an isometric view thereof in lowered position and illustrating the bottom together with the side and end shown in FIG. 1;

FIG. 3 is a perspective view illustrating the case in an open operative position; and

FIG. 4 is a rear elevation thereof in open position.

In FIGS. 2, 3 and 4 portions are broken away for convenience of illustration only, while in all views areas of the case are stippled to show contrast. The undisclosed end is a mirror image of the end shown.

The dominant features of the design are shown in full lines.

We claim:

The ornamental design for a case for a portable heater, as shown and described.
